The ornamental design for a bag for medical use, as shown and described.

DESCRIPTION

FIG. 1 is a perspective view of a first embodiment of a bag for medical use showing my new design;

FIG. 2 is a front elevational view thereof; a rear elevational view being a mirror image;

FIG. 3 is a right side elevational view thereof, a left side elevational view thereof being a mirror image; and

FIG. 4 is a bottom plan view thereof.

FIG. 5 is a cross sectional view thereof cut along the line 5-5 of FIG. 2;

FIG. 6 is an enlarged right side elevational view thereof taken between the lines 6-6 of FIG. 3; and

FIG. 7 is a partially enlarged cross sectional view thereof taken between the lines 7-7 of FIG. 5.

FIG. 8 is a perspective view of a second embodiment of a bag for medical use showing my new design;

FIG. 9 is a front elevational view thereof; a rear elevational view being a mirror image;

FIG. 10 is a right side elevational view thereof, a left side elevational view thereof being a mirror image; and

FIG. 11 is a bottom plan view thereof.

FIG. 12 is a cross sectional view thereof cut along the line 12-12 of FIG. 9;

FIG. 13 is an enlarged right side elevational view thereof taken between the lines 13-13 of FIG. 10; and

FIG. 14 is a partially enlarged cross sectional view thereof taken between the lines 14-14 of FIG. 12.

FIG. 15 is a perspective view of a third embodiment of a bag for medical use showing my new design;

FIG. 16 is a front elevational view thereof; a rear elevational view being a mirror image;

FIG. 17 is a right side elevational view thereof, a left side elevational view thereof being a mirror image; and

FIG. 18 is a bottom plan view thereof.

FIG. 19 is a cross sectional view thereof cut along the line 19-19 of FIG. 16;

FIG. 20 is an enlarged right side elevational view thereof taken between the lines 20-20 of FIG. 17; and

FIG. 21 is a partially enlarged cross sectional view thereof taken between the lines 21-21 of FIG. 19.

FIG. 22 is a perspective view of a fourth embodiment of a bag for medical use showing my new design;

FIG. 23 is a front elevational view thereof; a rear elevational view being a mirror image;

FIG. 24 is a right side elevational view thereof, a left side elevational view thereof being a mirror image; and

FIG. 25 is a bottom plan view thereof.

FIG. 26 is a cross sectional view thereof cut along the line 26-26 of FIG. 23;

FIG. 27 is an enlarged right side elevational view thereof taken between the lines 27-27 of FIG. 24; and

FIG. 28 is a partially enlarged cross sectional view thereof taken between the lines 28-28 of FIG. 26.

FIG. 29 is a perspective view of a fifth embodiment of a bag for medical use showing my new design;

FIG. 30 is a front elevational view thereof; a rear elevational view being a mirror image;

FIG. 31 is a right side elevational view thereof, a left side elevational view thereof being a mirror image; and

FIG. 32 is a bottom plan view thereof.

FIG. 33 is a cross sectional view thereof cut along the line 33-33 of FIG. 30;

FIG. 34 is an enlarged right side elevational view thereof taken between the lines 34-34 of FIG. 31; and

FIG. 35 is a partially enlarged cross sectional view thereof taken between the lines 35-35 of FIG. 33.

FIG. 36 is a perspective view of a sixth embodiment of a bag for medical use showing my new design;

FIG. 37 is a front elevational view thereof; a rear elevational view being a mirror image;

FIG. 38 is a right side elevational view thereof, a left side elevational view thereof being a mirror image; and

FIG. 39 is a bottom plan view thereof.

FIG. 40 is a cross sectional view thereof cut along the line 40-40 of FIG. 37;

FIG. 41 is an enlarged right side elevational view thereof taken between the lines 41-41 of FIG. 38; and,

FIG. 42 is a partially enlarged cross sectional view thereof taken between the lines 42-42 of FIG. 40.

The dash-dash broken lines illustrate portions of the bag for medical use that form no part of the claimed design. Dot-dash broken lines define the boundaries of the claim, and form no part of the claimed design.
